[57] CLAIM

I claim the ornamental design for an adapter end piece for penlights, as shown and described.

DESCRIPTION

FIG. 1 is a front perspective view of an adapter end piece for penlights showing my new design. A penlight and ear dam are illustrated in dash lines;

FIG. 2 is an enlarged perspective view thereof;

FIG. 3 is a side elevational view thereof;

FIG. 4 is an elevational view thereof taken from the end as seen from the right in FIG. 3;

FIG. 5 is a top plan view thereof;

FIG. 6 is a bottom plan view thereof;

FIG. 7 is an elevational view thereof taken from the end as seen from the left in FIG. 3;

FIG. 8 is a front perspective view of a modified adapter end piece for penlights wherein an ear wax extractor instrument has been added;

FIG. 9 is a top plan view thereof with the bottom view being a mirror image thereof;

FIG. 10 is an elevational view thereof taken from the end as seen from the right in FIG. 9;

FIG. 11 is a side elevational view thereof;

FIG. 12 is a front perspective view of a modified adapter end piece for penlights without any instrument being attached thereto;

FIG. 13 is a side elevational view thereof with the top, bottom and opposite sides being mirror images thereof;

FIG. 14 is an elevational view thereof taken from the end as seen from the right in FIG. 13;

FIG. 15 is a front perspective view of a modification of the adapter end piece for penlights of FIG. 13 wherein the right end of the adapter end piece is smaller in diameter;

FIG. 16 is a side elevational view thereof with the top, bottom and opposite side views being mirror images thereof, and,

FIG. 17 is an elevational view thereof taken from the end as seen from the right in FIG. 16.
